CHAIR BACK

Ir. R. Bromagem, Union City, Ind., assignor to
 Union City Body Company, Union City, Ind.,
 a corporation of Indiana

Application April 26, 1937, Serial No. 138,977

1 Claim. (Cl. 155—194)

My invention relates to improvements in theater chairs or chairs of the type of theater chairs. Primarily, my invention relates to the back structure and side structure of a theater chair.

5 It is one of the objects of my invention to provide a back structure for a theater chair which may be formed by stamping the same from a single sheet of material and with which may be integrated the side panel of the chair.

10 For the purpose of disclosing the invention, I have illustrated an embodiment thereof in the accompanying drawing, in which:

Fig. 1 is a side elevation of so much of a chair as is necessary for disclosing my invention;

15 Fig. 2 is a longitudinal sectional view taken on the line 2—2 of Fig. 1;

Fig. 3 is a transverse sectional view taken on the line 3—3 of Fig. 1; and

20 Fig. 4 is a side elevation, partially in section, of my chair back and its associated side panel.

In the embodiment of the invention illustrated, each side standard of a chair embodying my invention is preferably formed of a frame constructed of a T-bar bent into a substantially inverted U-shaped structure providing vertical legs 1 and 2 and a top cross-bar 3. Intermediate of the top and bottom, a U-shaped cross-bar 4 is secured between the legs 1 and 2, preferably by welding. The outer decorating or cover panel 5 is formed of sheet metal and is secured against the standard by means of a U-shaped channel member, one leg 6 of which is preferably welded to the inner face of the panel, the other leg 7 being adapted to take into the channel of the cross-member 4. The upper portion of the panel 5 is turned over the top arm 3 and is provided with a transversely extending groove 8 for a purpose to be more fully hereinafter explained.

The back 9 of the chair is formed from a single 40 piece of sheet metal being suitably bent and shaped to provide the proper curvature for the occupant's back and is provided with a pair of forwardly extending integral wings 10, these wings being bent forward on a rounded arc as at 45 about 11. Each of the forward wings is provided with a side panel 12 adapted to be secured to the standard 1. Each side panel 12 is integrated with a wing 10, being welded to a plate 10' in turn welded to the wing, as indicated in Figs. 3 and 4.

50 The front edge of the plate 10' is offset as at 10"

and this offset portion is welded to the panel 12. Furthermore, it will be noted that the rear edge of the plate 10', as shown at 10'', conforms in alignment to the bend 11 in the back 9. Therefore, each of the wings 10 is stiffened by the plate 5 10' but this stiffening effect stops substantially at the bend of the wing, thereby permitting the wings to be bent along a line parallel with the back to permit adjustment of the plate 12 to accommodate different angles at which the 10 standards may be set. The bottom edge of the side panel 12 is provided with an inturned portion 13 carrying a downwardly extended lip 14 adapted to take into the U-shaped cross-bar 4. The upper end of the panel 12 is provided with a 15 groove 15 similar to the groove 8 and engages over the top cross-bar 3. When the lip 14 is socketed in the cross-bar 4 and the outer and inner panels 5 and 12 lapped over the top cross-bar 3, a securing channel member 16 is slid into 20 the grooves and securely locks the two side panels together. This securing panel 16 carries the arm 17 of the chair.

The seat 18 of the chair is preferably secured on a stretcher rod 19 which is bolted into the 25 side panel 12.

Chairs of this character are arranged in the theater, as a rule, in rows, each forming the arc of a circle. This arc, of course, for different conditions, is variable and in order to accommodate this arc and to swing the side panels in or out in accordance with demands, it is very easy to bend the side panels and associated standards toward or away from each other on the line of the bend 11 in the chair. The structure, therefore, lends itself to ready assembly and mounting in the theater under varying conditions.

30 I claim as my invention:

A chair back comprising a back portion having at its opposite edges forwardly extending 40 wings and formed from a single sheet of metal, a side panel for connecting each wing with a support standard and a connecting plate welded respectively to each side panel and its associated wing, the rear edge of said plate extending substantially parallel with the chair back to provide 45 a bend line parallel with the bend line in the wing parallel with the chair back.
